UNITED STATES PATENT OFFICE.

HAROLD J. BELL, OF GLOUCESTER CITY, NEW JERSEY, ASSIGNOR TO THE WELSBACH INCANDESCENT GAS LIGHT COMPANY, OF NEW JERSEY.

ATMOSPHERIC GAS-BURNER.

SPECIFICATION forming part of Letters Patent No. 396,255, dated January 15, 1889.

Application filed May 10, 1888. Serial No. 273,455. (No model.)

To all whom it may concern:

Be it known that I, HAROLD J. BELL, a citizen of the United States, residing at Gloucester City, in the county of Camden and State of New Jersey, have invented new and useful Improvements in Atmospheric Gas-Burners, of which the following is a specification.

This invention relates to atmospheric gas-burners for incandescent gas-lighting; and it consists in the combination of a tube provided at or near its lower end with lateral air-inlets, so located as to allow said tube to be secured into a base a sufficient distance to hold it firm without obstructing any part of said air-inlets, and a vertically-adjustable shield having a neck adapted to close said air-inlets or any part of them at will, a spiral ring being secured to the inner wall of the shield and concentric therewith to engage an external spiral groove or thread on the above-mentioned base, whereby a rotation of the shield will cause its adjustment on the tube in an upward direction to partially or wholly expose the air-inlets (under the shield) for the purpose of admitting a lesser or greater quantity of air to be mixed with the gas before it is burned, or in a downward direction to absolutely close said air-inlets as the nature of the gas used may require.

The invention is illustrated in the accompanying drawings, in which—

Figure 1 is a perspective view of my improved atmospheric gas-burner tube with shield lowered to close the air-inlets. Fig. 2 is a vertical section of the same with shield elevated to expose the air-inlets. Fig. 3 is an elevation of the burner-tube and base with shield detached. Fig. 4 is an inverted plan of the shield with internal spiral ring.

The burner-tube 1 is provided with the usual lateral air-inlets, 2, and beneath these air-inlets it may have a horizontal finely-perforated plate or disk, 3, to divide the supply of gas into fine currents, whereby an intimate mixture of gas and air can be produced in the tube. The base of this tube 1, beneath the perforated disk 3, is internally screw-threaded to engage a gas-fixture. A burner tip or spreader of any desired construction suitable for incandescent gas-lighting can be

placed in or upon the upper end of the tube in order to control the quantity of air admitted through the inlets 2, and thereby regulate the intensity of the flame. An adjustable bell-shaped shield, 4, is supported on the base of the burner-tube 1 in such a manner as to be capable of vertical movement to cover and uncover the air-inlets 2. This shield is provided at the top with a neck, 8, the internal diameter of which is equal to the external diameter of the tube 1 and the length of which is slightly greater than the diameter of the air-inlets 2. The shield is also provided internally with a spiral ring, 5, located at about its center and supported therein at a distance from its walls by means of one or more arms, 6, so as to afford an air-passage between said ring and the walls of the shield equal in area to the air-inlets 2 in tube 1. The ring 5 engages an external screw-thread or spiral groove, 7, formed on the base of the tube 1, below the lateral air-inlets 2, so that by rotating the shield in the proper direction its neck 8 will cover or uncover the air-inlets 2, as may be desired. It will be observed that when the shield is raised, as shown in Fig. 2, a sufficient distance the air has free access to air-inlets 2, and yet the bottom of said shield hangs far enough below the air-inlets 2 to arrest the disturbing influences of external air-currents, being assisted, moreover, by the partial obstruction offered by the spiral ring 5.

What I claim is—

The combination, with an atmospheric gas-burner tube having lateral air-inlets 2 and provided with an externally screw-threaded or spiral-grooved base, 7, of a vertically-adjustable bell-shaped shield having a spiral ring, 5, to engage the external spiral groove on the base of the burner-tube, and a neck, 8, to cover or uncover the lateral air-inlets, substantially as described.

In testimony whereof I affix my signature in presence of two witnesses.

HAROLD J. BELL.
